PEG BOARD TOY

Henry R. Redka, Bronx, N.Y.

Application September 4, 1957, Serial No. 47,601

Term of patent 14 years

(Cl. D34—15)

Fig. 1 is a perspective view of a peg board toy, showing the new design; and

Fig. 2 is a side elevational view thereof.

The dominant feature of my design resides in the portions shown in full lines.

I claim:

The ornamental design for a peg board toy, substantially as shown and described.
